UNITED STATES PATENT OFFICE

158,360

COMBINED TURBOELECTRIC GENERATOR AND LAMP HOUSING

Wilfrid Henry Davis, Duffield, near Derby, England, assignor to Joseph Lucas Limited, Birmingham, England, a company of Great Britain

Application February 24, 1948, Serial No. 144,711
In Great Britain July 25, 1947

Section 1, Public Law 690, August 8, 1946

Term of patent 14 years

(Cl. D48—24)

To all whom it may concern:

Be it known that I, Wilfrid Henry Davis, a subject of the King of Great Britain and Northern Ireland, residing at The Kirkstyes, Duffield, near Derby, England, has invented a new, original, and ornamental Design for a Combined Turboelectric Generator and Lamp Housing, of which the following is a specification, reference being had to the accompanying drawing, forming part thereof.

In the drawing:

Figure 1 is a side view of a combined turboelec-

tric generator and lamp housing showing my new design.

Figure 2 is a top plan view thereof, and
Figure 3 is a bottom plan view.

I claim:

The ornamental design for a combined turboelectric generator and lamp housing, as shown.

WILFRID HENRY DAVIS.
